UNITED STATES PATENT OFFICE.

MARTIN W. POND AND LYMAN W. DARLING, OF ELYRIA, OHIO.

HARNESS BREAST-STRAP SLIDE.

Specification forming part of Letters Patent No. 41,320, dated January 19, 1864.

To all whom it may concern.

Be it known that we, MARTIN W. POND and LYMAN W. DARLING, of Elyria, in the county of Lorain and State of Ohio, have invented a new and useful mode of protecting the breast-straps of team-harnesses from the chafing wear of the neck-yoke rings; and we do hereby declare that the following is a full and exact description thereof, reference being had to the accompanying drawings, and to the letters of reference marked thereon, in which—

The figure represents a perspective view.

The nature of our invention consists in providing the ordinary breast-strap of team-harness with a metallic shield secured to a suitable leather loop, which slides over the breast-strap and supports the rings of the neck-yoke and protects the strap from chafing and wearing. It also allows the pole of a wagon to vibrate more freely than it otherwise would, thus preventing any undue wrenching or sudden jerking of the horses.

To enable others skilled in the art to make and use our invention, we will proceed to describe its construction and operation.

A represents a concavo-convex metallic plate, which is secured firmly to curved leather loop B, through which the breast-strap passes. a a are small, stout, curved, conically-formed projections, which start out from their base and project in an oblique direction on a curve toward the opposite side of the plate A, slightly passing its center, as seen in the draw-

ings. The lines of their divergence, being parallel, are such as will freely admit the ring of the neck-yoke when turned to the proper angle of obliquity. After passing below the ends of the projections it naturally assumes a position at right angles to the shield-plate. The inside curve of the projections are such that, in connection with the curve of the base-plate, it forms an oval, the extremities of which are immediately at the base of the projections, and forms a secure seat wherein the ring is held in case the plate is tilted toward either end, thus effectually (in combination with flanges c c) preventing the shield from being turned over or upside down, as would be the case without this device.

The advantages of this device are too obvious to need comment.

What we claim as new, and desire to secure by Letters Patent, is—

The metallic shield having its curved diverging projections, and being secured firmly to a suitable loop of leather for the purpose of protecting the breast-strap of harnesses from the chafing and cutting of the rings of the neck-yoke, the whole being constructed and arranged in the manner substantially as set forth.

MARTIN W. POND.
LYMAN W. DARLING.
